US00D622680S

(12) **United States Design Patent**
Lin et al.

(10) **Patent No.:** US D622,680 S
(45) **Date of Patent:** ** Aug. 31, 2010

(54) **PACKAGE OF A LIGHT EMITTING DIODE**

(75) Inventors: **Chen-Hsiu Lin**, Taipei (TW); **Yi-Fei Lee**, Taipei (TW); **Chang-Yen Lin**, Taipei (TW)

(73) Assignees: **Silitek Electronic (Guangzhou) Go., Ltd.**, Guangzhou (CN); **Lite-On Technology Corp.**, Taipei (TW)

(**) Term: **14 Years**

(21) Appl. No.: **29/347,322**

(22) Filed: **Dec. 4, 2009**

(51) **LOC (9) Cl.** 13-03

(52) **U.S. Cl.** D13/180

(58) **Field of Classification Search** D13/180;

D26/2; 257/79, 80, 81, 88, 89, 95, 98, 99;
257/100, E33.058; 313/483, 498, 500; 362/555,
362/800

(57) **CLAIM**

The ornamental design for package of a light emitting diode, as shown and described.

DESCRIPTION

FIG. 1 is a perspective view of package of a light emitting diode showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
